UNITED STATES PATENT OFFICE.

EDWIN JONES, OF CLEVELAND, OHIO.

UNCOUPLING DEVICE FOR CAR-COUPINGS.

1,347,380.

Specification of Letters Patent. Patented July 20, 1920.

Application filed August 28, 1919. Serial No. 320,350.

To all whom it may concern:

Be it known that I, EDWIN JONES, a citizen of the United States, residing at Cleveland, in the county of Cuyahoga and State 5 of Ohio, have invented certain new and useful Improvements in Uncoupling Devices for Car-Couplings; and I do declare the following to be a full, clear, and exact description of the invention, such as will enable 10 others skilled in the art to which it appertains to make and use the same.

This invention relates generally to railway draft appliances, but more particularly to uncoupling devices for car couplers.

15 The primary object of the invention is to provide a device by which the locking pin of a car coupler is connected to the operating or uncoupling rock shaft, said device being constructed so that it can be easily and 20 quickly applied to the car coupler or removed therefrom, and not having small parts such as bolts, nuts, washers and cotter pins which become easily broken and lost.

Another object of the invention is to generally improve upon devices of this nature by the provision of an extremely simple, strong, durable and inexpensive in construction, one which will be efficient and reliable in operation and well adapted to the purpose 25 for which it is designed.

With these and other objects in view, the invention consists of certain novel features of construction, and the combination and arrangement of parts as will be hereinafter 30 fully described and claimed.

In the accompanying drawings forming a part of this specification, and in which similar reference characters designate like parts throughout the several views,

40 Figure 1 is a perspective view of a portion of a railway car, showing a device constructed in accordance with this invention applied to the coupler and uncoupling rock shaft;

45 Fig. 2 is a side view of the device;

Fig. 3 is a front view of the same; and,

Fig. 4 is a transverse sectional view taken on the plane indicated by the line 4—4 of Fig. 3.

50 In the embodiment illustrated the numeral 1 designates a car coupler which is of any standard construction and is provided with a coupling knuckle 2 and a vertically movable locking pin 3. As is usual with devices of this character the locking pin 3 serves to lock the knuckle 2 in closed

position when in its lowermost position. Mounted in brackets secured to the end of the car is a rock shaft 5, the latter extending transversely of the car from the central portion thereof to one side and being provided with an operating arm or handle 6 at one end and a lifting arm 7 at the other end. The free end of the lifting arm 7 is disposed substantially above the locking pin 3 and is provided with an eye 8. The upper end of the locking pin 3 is provided with an eye 9.

This invention comprises a link connected to the locking pin 3 and a connector or clevis 70 carried by the lifting arm 7. The link is substantially U-shaped in configuration being formed from a single length of metal and being bent at approximately its middle to form a pair of spaced arms 10 and 11. 75 The ends of the arms 10 and 11 adjacent the intermediate portion 12 of the link are offset outwardly as at 13 and 14 respectively, the offset portion 13 of the arm 10 only extending a slight distance from the 80 intermediate portion 12 of the link while the offset portion 14 of the arm 11 extends a greater distance from the intermediate portion 12 of the link. The upper ends of the arms 10 and 11 are turned upon themselves 85 to form open hooks 15.

The aforementioned connector or clevis is also formed from a single length of metal and comprises a straight portion 16 having one end bent upon itself to form an open 90 eye 17 and its other end bent laterally as at 18. The lateral portion 18 of the clevis is then formed into an eye 19 arranged in a plane parallel to the plane of the eye 17, this being accomplished by bending the 95 lower end of the portion 18 at right-angles to said portion and then upon itself into a U-shape. As clearly shown in Fig. 4 of the drawings the eye 19 is slightly contracted.

100 The link is connected to the locking pin 3 by inserting the free end of one of the hooks 15 through the eye 9 of the locking pin and then turning or swinging the link and sliding it through the eye until the intermediate portion 12 is extended through the eye. The link should be connected to the locking pin so that the hooks 15 extend rearwardly. The clevis is inserted through the eye 8 of the lifting arm 7 by inserting 110 the free end of the eye 17 into the eye 8 and then turning the clevis as it is being slid into

the eye. The eye 8 should be disposed adjacent the straight portion 16 of the clevis. With the link connected to the locking pin and the clevis connected to the lifting arm in the manner just described, these two parts are coupled together by positioning the straight portion 16 in the eyes formed by the hooks 15. The clevis is then rotated or swung upon its straight portion 16 as an axis so that the free end of the eye 17 will pass around the outer curve of the hook 15 of the arm 11 and become coupled thereto and so that the eye 19 will pass around the hook 15 of the arm 10. After the clevis has been swung a certain distance the contracted end of the eye 19 will engage the adjacent edge of the arm 10 and when this occurs the eye 19 must be forced open so that the arm 10 will pass into the same. The eye 19 can be forced open by slightly tapping the closed end of the same with a hammer.

With the clevis and link connected in this manner it will be seen that the clevis has a slidable movement upon the arms of the link but this movement is limited in its upward direction by the hooks 15 which consequently serve in the capacity of stops. The sliding movement is for the purpose of preventing the locking pin 3 from accidentally being raised as the lifting arm 7 is moved slightly up and down by the vibration of the car. To uncouple the car it is only necessary to swing the handle 6 so as to rock the shaft 5 and lift the arm 7. As soon as the straight portion 16 of the clevis engages beneath the hooks 15 relative sliding movement of the clevis with respect to the link will end and the link will be raised thereby lifting the locking pin.

Should it be desired to disconnect the clevis from the link it is only necessary to raise the clevis until the straight portion 16 is disposed adjacent the hooks 15, then snap or force the eye 19 open until it becomes disengaged from the arm 10 and then to rotate or swing the clevis so that the free end of the eye 17 travels around the hook 15 carried by the arm 11. As soon as the free end of the eye 17 clears the free end of the hook 15 the clevis will be disconnected from the link.

Much importance is paid to the fact that both the link and the clevis can be connected to the car coupler and uncoupling device without modifying the construction of the same, and without in any way disconnecting these parts from the car. Much importance is also to be paid to the fact that the invention consists of no small parts such as bolts, nuts, washers or cotter pins which become easily broken and lost, and which require considerable time and trouble to assemble them to their proper places. With only two parts to the invention, there is nothing to become easily broken or lost, and they can be easily and quickly applied to the car or

removed therefrom. Another important characteristic which the invention has is that the clevis and the link may be quickly and easily disconnected while the clevis remains attached to the releasing member.

Various changes in form, proportion, and in the minor details of construction may be resorted to without departing from the spirit of the invention as defined in the claims.

What is claimed is:

1. A device for connecting a movable locking member and a movable releasing member together comprising a link carried by the locking member, a connector carried by the releasing member, and coating means carried by said link and said connector for slidably coupling said link to said connector, said means being arranged for disengagement by a rotary movement of said connector with respect to said link, whereby to detach said connector from said link while said connector remains attached to said releasing member.

2. The combination of a car coupler having a vertically movable locking pin, a substantially U-shaped link connected at its intermediate portion to said pin, a lifting arm having its free end disposed above said pin and between the arms of said link, a clevis loosely connected to the free end of said lifting arm and slidably connected to the arms of said link, and open hooks formed at the free ends of the arms of said link for limiting the sliding movement of said clevis upon the same, said clevis being adapted to be swung around said hooks to effect an uncoupling of said clevis from said link.

3. The combination of a car coupler having a vertically movable locking pin, a substantially U-shaped link connected at its intermediate portion to said pin, a lifting arm having its free end disposed above said pin and between the arms of said link, a clevis loosely connected to the free end of said lifting arm and provided with eyes for slidably receiving the arms of said link, and open hooks formed at the free ends of the arms of said link to ordinarily limit the sliding movement of said clevis upon the same, said clevis being adapted to be swung so that its eyes will pass around said hooks to effect an uncoupling of said clevis from said link.

4. The combination of a car coupler having a vertically movable locking pin, a substantially U-shaped link connected at its intermediate portion to said pin, a lifting arm having its free end disposed above said pin and between the arms of said link, a clevis loosely connected to the free end of said lifting arm and provided with eyes for slidably receiving the arms of said link, one of said eyes having a contracted end, and open hooks formed at the free ends of the

arms of said link for ordinarily limiting the sliding movement of said clevis on the same, the contracted eye of said clevis being adapted to be sprung open so that the respective arm of said link will pass out of the same and said clevis can be swung so that the other eye will pass around its respective hook to effect an uncoupling of said clevis from said link.

5. The combination of a car coupler having a vertically movable locking pin, a substantially U-shaped link connected at its intermediate portion to said pin, the inner ends of the arms of said links being offset 10 outwardly, the offset portions being of different lengths, a lifting arm having its free end disposed above said pin and between said arms, a clevis formed from a single length of metal and having a straight portion 15 extending through said lifting arm and an eye formed at one end of said

straight portion, the other end of said straight portion being bent at right-angles and the free end of this portion being bent at right-angles and turned upon itself to 25 form another eye disposed in a plane parallel to the plane of the first eye, the second eye having a contracted end, said eyes slidably receiving the arms of said link, and open hooks formed at the free ends of the 30 arms of said link for ordinarily limiting the sliding movement of said clevis upon the same, the contracted eye of said clevis being adapted to be sprung open so that the respective arm of said link may be passed out 35 of the same and said clevis may be swung so that its other eye will pass around its respective hook to effect an uncoupling of said clevis from said link.

In testimony whereof I have hereunto set 40 my hand.

EDWIN JONES.
